CLAIM

The ornamental design for a round pot holder, as shown and described.

DESCRIPTION

FIG. 1 is a first perspective view of a round pot holder showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the round pot holder in which the design is embodied that form no part of the claimed design.

1 Claim, 8 Drawing Sheets
